US00D816527S

(12) **United States Design Patent** (10) **Patent No.:** **US D816,527 S**
Ramasarma et al. (45) **Date of Patent:** **** May 1, 2018**

(54) **WEARABLE PERSONAL IDENTIFICATION DEVICE**

(71) Applicant: **Blazer and Flip Flops, Inc.**, San Diego, CA (US)

(72) Inventors: **Vaidyanathan Pallavur Ramasarma**, San Diego, CA (US); **Maximillian Philip Burton**, San Francisco, CA (US); **Quinn Huffstetler**, San Francisco, CA (US); **Dustin Lee**, San Francisco, CA (US); **Adam Leonards**, San Francisco, CA (US)

(73) Assignee: **Blazer and Flip Flops, Inc.**, San Diego, CA (US)

(**) Term: **15 Years**

(21) Appl. No.: **29/573,904**

(22) Filed: **Aug. 10, 2016**

(51) **LOC (11) Cl.** **10-05**

(52) **U.S. Cl.**

USPC **D10/104.1**

CLAIM

The ornamental design for a wearable personal identification device, as shown and described.

DESCRIPTION

FIG. 1 is a perspective view of a wearable personal identification device showing our new design;

FIG. 2 is a front view of the wearable personal identification device;

FIG. 3 is a rear view of the wearable personal identification device;

FIG. 4 is a right side view of the wearable personal identification device;

FIG. 5 is a left side view of the wearable personal identification device;

FIG. 6 is a top view of the wearable personal identification device; and,

(Continued)

FIG. 7 is a bottom view of the wearable personal identification device.

1 Claim, 5 Drawing Sheets
